UNITED STATES PATENT OFFICE.

ALFRED KOEHN, OF NEW YORK, N. Y.

DESIGN FOR A LAMP-BRACKET.

SPECIFICATION forming part of Design No. 21,818, dated August 30, 1892.

Application filed June 27, 1892. Serial No. 438,218. Term of patent 3½ years.

To all whom it may concern:

Be it known that I, ALFRED KOEHN, of New York, in the county and State of New York, have invented a new and original Design for 5 Bracket Light-Fixtures; and I do hereby declare that the following is a full and exact description thereof, reference being had to the accompanying drawing, and to the letters of reference marked thereon, making a part of this specification.

My invention relates to a design for a bracket for supporting wall or side lights; and it consists in the configuration of such bracket.

The drawing shows an elevation of a bracket embodying my design.

The leading feature of my design consists

in the main body or part A, made in the conventional shape of a horn with its larger end up and ornamented by a cap B and having near its middle portion a band C, from which depends the arm D, of the scroll shape shown, connecting the main part A to the plate E.

I claim—

The design for a bracket, substantially as herein shown and described.

In testimony whereof I have signed my name to this specification in the presence of two subscribing witnesses.

ALFRED KOEHN.
